UNITED STATES PATENT OFFICE

ABEL DEFRAANCE AND PIERRE VERSILLÉ, OF PARIS, FRANCE

COMBINED MIXING AND VAPORIZING DEVICE

Application filed October 9, 1926, Serial No. 140,656, and in France June 25, 1926.

In order to improve the fuel mixture supplied to internal combustion engines, devices have already been proposed which act by a vaporizing process upon the liquid particles contained in the mixture leaving the carburettor. These devices in which vaporization is influenced by heating, were provided with heating blocks, placed between the carburettor and the engine, and with 5 channels for the passage of the carburetted mixture, a device being provided to close certain channels and thus to vary the number of the channels remaining open.

The device according to our invention likewise comprises a block provided with channels, this block being similarly disposed between the carburettor and the engine, but in which the improvement of the mixture is not effected by vaporization but exclusively or 10 chiefly by more thoroughly breaking up and atomizing the liquid particles of the mixture.

This object is attained by lodging within each channel of said block an atomizer element formed by a cylindrical solid core which is provided with a number of longitudinal ribs cut out in one or several points so as to lay bare the central core and form at these 15 points intermediate expansion or whirling chambers; furthermore a valve or closing device is provided disposed to close successively the outlet orifices of the channels thereby varying the number of channels giving free passage to the mixture according to the 20 prevailing operating stages.

In this manner the mixture is divided into a number of small partial streams each of which is treated separately by the corresponding atomizer element. By suitably regulating the closing valve the treatment will be alike for all the partial streams which will consequently be of a same nature and can 25 without any difficulty be subsequently re-united so as to form, upon leaving the block a single stream of a perfectly homogeneous mixture.

According to another embodiment, the valve controlling the outlet orifice of the 30 channels can be formed by the atomizer ele-

ments proper which are suitably arranged and disposed to this effect.

In the annexed drawings Figs. 1 and 2 show by way of example one embodiment of the invention in longitudinal sections taken at 90° to each other; this apparatus is adapted to be mounted upon the suction conduit extending from the carburettor to the engine. Figs. 3 and 4 are similar views of an apparatus showing certain variations; this apparatus can be mounted directly upon the cylinder. Fig. 5 shows in transverse section a part of block with one of its atomizer elements. Fig. 6 is a perspective view of an atomizer element. Figs. 7, 8 and 9 show on 60 an enlarged scale a modification in which the regulation of the free passage sections in each atomizer element is obtained by changing the position of the atomizer which acts at the same time as a closing device. Fig. 70 10 is a side elevation of a motor equipped with the modifications of the invention.

The apparatus shown in Figs. 1 and 2 comprises a body 1 of which one side may be connected by means of a flange 1' to the induction conduit of the engine, and the other side by a socket 2 and a flange 2' to the conduit of the carburettor. Conduits 3 are provided within the body 1 for the circulation of a heating fluid (such as the exhaust-gases, hot 75 water, etc.). The part of the body surrounded by the heating conduit 3 forms a block 4 with channels 5 containing the atomizer element 8 for mixture flowing from the carburettor to the engine; the outlet orifices of the 80 channels 5 can be closed by a plug of a valve 6, the port of which can be traversed by the mixture. Each of the atomizers 8 comprises a series of ribbed cylindrical cores 8' with the narrow longitudinal slots 8'' formed between 85 these ribs; the latter are divided in two or more sections over the length of the atomizer element leaving the cylindrical core 8' free at the intersection of these divisions thereby 90 forming expansion chambers around the central part 8' so that the mixture will be successively subjected to wire drawing and expansion actions.

The ribbed atomizer elements may be secured in place by any suitable means, and 100

the outlet orifices of the channels 5 are controlled directly by the plug of the valve 6.

One feature of the invention consists in the connections of this valve 6 to the operating mechanism of the carburettor throttle, said valve 6 being opened proportionally to the opening of the throttle itself; the number of atomizers 8 uncovered by the valve 6 and consequently the free section for the passage of the mixture will thus for all loads and at all times correspond to the quantity required by the engine, and the improvement of the mixture by the use of atomizer blocks will consequently be realized at all engine loads.

Another feature consists in varying the number of atomizers 8 uncovered by the valve 6 so as always to maintain constant the influence of the atomizer block, upon the fuel during the various loadings of the engine. This may be attained by providing in the heating medium supply conduit of the body 1 and to operatively connect this valve to the carburettor throttle, so that the free passage section for the heating fluid will increase when the throttle of the carburettor closes. It is a well known fact that in apparatus utilizing a branch conduit of the exhaust gases for heating purposes, this method of increasing the temperature gives rise to many inconveniences; if the branch is for instance designed for full loads, the heating capacity will increase simultaneously with the lowering of the speed of flow of the hot gases, and it will eventually at a given moment, fall to naught. The device described obviates this drawback.

Fig. 10 shows an engine equipped according to the invention. E shows the control lever of the throttle for the carburettor mixture supplied by the carburettor C. A shows the atomizer apparatus according to the invention, set in between the carburettor C and the induction conduit B of the engine. According to the invention, the control lever 7 of the valve 6 is operatively connected by a rod 9 to the control lever E of the throttle of the carburettor; the latter is controlled by the pedal P of the accelerator and a connecting rod 10.

The arrangement shown in Figs. 3 and 4 is the same as those described above with the exception that the valve 6 is formed by a hollow valve plug which is open at one end so that the mixture will flow in the direction of the arrows (Fig. 3) and that the apparatus can be mounted directly upon the cylinder head of the engine by any suitable means, such as a flange 12.

The atomizer elements can be mounted for sliding movement within their blocks, as shown in Fig. 7, their end portion terminating in a male truncated cone section 13 while the end of the channel 5 forms a corresponding female cone portion 14; thus the full cone at the end of the core 8' may be engaged by

the seat 14 when the element 8 is pushed upwards and thus completely closes the passage of the channel 5, while, by lowering said element 8, a free passage is left corresponding to the section of the free passage through the slots 8''. Springs 15 are provided which urge the atomizers in a downward direction tending to open the passage, while the control elements 6_a operate to lift the atomizers successively within their channels and press the cone shaped parts against their seats so as to close the passage for the carburetted mixture. Fig. 8 shows one atomizer element in its upper position, the passage being closed; Fig. 9 shows this element in its lowered position, the passage being open. The control elements 6_a which in this case are substituted for the valve 6 are keyed upon its shaft 16, coupled by two cog-wheels 17 keyed upon the same shaft 16, and operatively connected by the control lever 7_a (Figs. 7 and 10) and the rod 9 to the control lever of the throttle valve of the carburettor. It is clear that the position of the sliding atomizer elements and of its driving gear may be changed at will.

Similarly the detail constructions may be greatly varied without departing from the spirit of the invention.

It is to be noted that the devices described above may be adapted without any modification to existing engines or carburettors.

We claim:

1. In a device for improving the fuel mixture, more particularly adapted for internal combustion engines using heavy fuel, in combination a block provided with a series of channels extending therethrough for the passage of the mixture, a conical seat formed upon the outlet end of each channel, a mixing element mounted for sliding movement in each of said channels and formed of a central core with external radial ribs which are circumferentially slotted in at least one place in the length thereof so as to form in each channel at least one expansion chamber, a plain conical part formed at one end of the core of each mixing element and adapted to cooperate with the conical seat of the respective channel, a return spring fixed to and surrounding the opposite end of each element urging the same into its opening position, and a controlling device operatively connected to the throttle of the carburettor capable of moving the several mixing elements back and forth in their respective channels.

2. In a device for improving fuel mixture, particularly adapted for internal combustion engines using heavy fuel, in combination, a block provided with a plurality of channels, said channels being restricted at the upper ends thereof to form valve seats, a mixing element slidably mounted within each of said channels provided with a valve head and comprising a central core having

external radial ribs which are circumferentially slotted in at least one place in the length thereof so as to form in each channel at least one expansion chamber and means 5 for controlling the movement of the mixing elements.

3. In a device for improving fuel mixture, particularly adapted for internal combustion engines using heavy fuel, in combination, a 10 block provided with a plurality of channels, said channels being restricted at the upper ends thereof to form valve seats, a mixing element slidably mounted within each of said channels provided with a valve head and comprising a central core having external radial ribs which are circumferentially slotted in at least one place in the length thereof so as to form in each channel at least one expansion chamber, and control elements 15 operatively connected to the throttle of the carburettor disposed to move the mixing elements back and forth in their respective channels.

4. In a device for improving fuel mixture, particularly adapted for internal combustion engines using heavy fuel, in combination, a 20 block provided with a plurality of channels, a mixing element within each of said channels and comprising a central core having external radial ribs which are circumferentially slotted in at least one place in the length thereof so as to form in each channel at least one expansion chamber and means operatively connected to the throttle of the carburettor and controlling the outlet of the channels for the carburetted mixture. 25
